MATCH BOOK

Carl E. Anderson, Chicago, Ill., assignor to Arrow Match Corporation, Chicago, Ill.

Application December 8, 1942, Serial No. 468,268

1 Claim.

(Cl. 206—29)

My invention relates to match books and more particularly to the fastening means for the contents thereof. In the conventional match book, the matches are cut from cards of pasteboard, two such cards being deposited in the bottom fold or receptacle of the match book. The assembly of the receptacle and match card is then secured with a wire staple. While this type of fastening has been found efficient, it is my primary object to devise a different form of fastening to supplant the wire staples and for use in case there is a shortage of wire or advantage in changing the material of the fastener.

I have therefore devised a novel form of fastening means for the above purpose, the particular object of the same being to use the material of the match book receptacle and the match cards in an inter-locking manner to prevent the cards from leaving the match book receptacle when a single match is pulled out.

Another object of the improvement is to secure the bottom receptacle of the match book by binding means to firmly hold the match cards in the receptacle.

An additional object of the invention is to provide a fastening means which serves the additional purpose of an abrasive strip on which to light the matches.

An important object of the invention is to construct the novel fastening means along lines of extreme simplicity, in order that the cost of the match book may be kept at a minimum.

With the above objects in view and any others which may suggest themselves from the description to follow, a better understanding of the invention may be had by reference to the accompanying drawing, in which—

Figure 1 is a frontal perspective view of the improved match book with its cover open;

Figure 2 is a similar view from the rear;

Figure 3 is an elevation of the receptacle portion of the match book, with the abrasive strip broken away;

Figure 4 is a view similar to Figure 3, with the front wall of the receptacle broken away; and

Figure 5 is a horizontal section on the line 5—5 of Figure 1.

Referring specifically to the drawing, 10 denotes the back of a typical match book, 11 the frontal cover, 12 the bottom receptacle and 13 the front wall of the latter.

As indicated in Figure 4, the matches 14 are cut from a card 15, and it is customary to place two of the match cards in the receptacle 12 to

form the contents of the match book, as previously stated.

While the front wall 13 of the receptacle 12 in the conventional match book is employed for the driving of the wire staple, I also employ such wall initially for the fastening of the match cards 15, but without driving any staple or other fastening device into the same. Instead, a flat pointed, blunt tool is driven into the wall 13 at a number of places in a horizontal course after the match cards 15 have been deposited into the receptacle 12, as indicated in Figure 5. Primarily, the tool is intended to perforate only the wall 13 and the first match card, and indent the second match card, as shown. The action of the tool causes pairs of inwardly extending tongues 15a to be formed in the perforated zones, such tongues interlocking the material of the wall 13 and the cards against separation. Thus, as long as the wall 13 is positioned next to or against the match cards 15, an ordinary amount of pull on the match cards will not draw them out of the receptacle; and they will be sufficiently secure to withstand the individual pull on the matches as they are needed.

In order that the front wall 13 of the receptacle may remain in proper position at all times to serve as stated, it is reinforced by the application of a horizontal external strip or ribbon 16 of thin paper, the ribbon being continued to span the ends of the receptacle as indicated at 17 and overlapping the back 10 of the match book on the rear side as indicated in Figure 2. The strip 16 is secured by means of adhesive or it may be made in gummed form for application by moistening.

The conventional match book carries a coating of abrasive on the receptacle wall 13 in the form of a horizontal bar. The direct application 40 of the abrasive is eliminated in the new embodiment, the strip 16 being coated with the abrasive beforehand. Thus, the strip by being applied as stated not only serves as a binder to keep the receptacle wall 13 in engagement with the match cards, but also serves as the abrasive element of the match book. The full lines in Figure 2 show the abrasive strip 16 as extending only partly over the back 10 of the match book, but the strip may be extended from both sides to the center of 45 such back, as indicated by dotted lines, in case an abrasive surface on the back of the match book is also desirable.

It will be evident from the above description that I have provided a fastening device which employs only one extra part, and in a secondary

sense, to serve its purpose. As stated, the interlocking structure of the match book and its contents forms a primary fastening and is secure against incidental or accidental pulling or dislodging strain imposed on the match group. However, the application of the abrasive strip 16 insures the retention of the fastened assembly in intimate relation to render it firm, the strip 16 serving the additional function of an abrasive which not only has a longer course than the conventional abrasive bar but may be duplicated on the back of the match book for additional use. These features are provided without extra parts other than the binding strip 16 which is of paper, and whose cost is nominal. A match book is thus had which uses no metal whatever and employs simple and efficient fastening means.

While I have described the improved match book along specific lines, it is apparent that minor changes or refinements may be made therein without departing from its principle, and I desire to consider such changes and refinements

as coming within the scope and spirit of the appended claim.

I claim:

A match book comprising a folded unitary sheet of material constituting a back wall, a frontal cover connected at one end to said back wall and a short front wall connected to the other end of said back wall and overlying the lower end of the latter, said short front wall and back wall forming a receptacle, a card of matches having its lower portion seated in said receptacle, said lower portion having a plurality of spaced recesses, integral tongues struck from said short front wall projecting into and interlocking with the recesses in the lower portion of said card within the receptacle, and a strap on said front wall extending over the side edges of the book and secured to said back wall for maintaining said tongues interlocked with said recesses to inhibit both transverse and longitudinal movement of said card with respect to said walls.
